DANIEL TRACY, OF GREAT FALLS, MONTANA.

MOLD.

1,148,939.

Specification of Letters Patent. Patented Aug. 3, 1915.

Application filed July 1, 1914, Serial No. 848,410. Renewed June 16, 1915. Serial No. 34,552.

To all whom it may concern:

Be it known that I, DANIEL TRACY, a citizen of the United States, residing at Great Falls, in the county of Cascade and State of Montana, have invented certain new and useful Improvements in Molds, of which the following is a full, clear, and exact description, reference being had to the accompanying drawings, forming a part hereof.

10 My invention has relation to improvements in molds; and it consists in the novel features of construction more fully set forth in the specification and pointed out in the claims.

15 In the drawings, Figure 1 is an end elevation of the bottom section of the mold and base thereof (partly broken) showing the application of the pouring ladle thereto; Fig. 2 is a vertical middle section of said base and bottom section; Fig. 3 is an enlarged side elevation of the mold showing the base and a number of sections thereof assembled, and being partly in section; Fig. 4 is a horizontal section on the line 4—4 20 of Fig. 3; and Fig. 5 is a bottom view of one of the sections of the mold following the bottom section of the series.

The present invention is particularly directed to molds for casting copper billets 30 employed in the manufacture of seamless copper tubing, the principal object sought being to construct a mold which will permit the pouring of the fused metal therewithout the danger of the same splashing against the walls of the mold.

The invention has special significance where applied to deep and narrow molds for making castings whose depth, while the mold is in casting position, equals or exceeds 40 the diameter of any cross-section through the casting; and it is to be understood that the invention is not to be limited to the casting of copper billets, but contemplates the casting of copper or other metal or composition or combination of metals in forms requiring a deep and narrow mold as above defined. In casting copper billets it has been the custom to pour the molten copper entirely from above the mold. Sometimes 50 the mold was made of two sections which were filled in succession, the second section being superposed on the first as soon as the first section was filled, the second section being immediately filled before the metal in 55 the first section had set. The two sections produced one continuous billet and natur-

ally reduced the height from which the copper had to be poured, by about one-half. However, this height was still so great that the impact of the steam against the hard 60 bottom of the mold produced splashing at the commencement of the pouring, said splashing in a large measure striking or coming in contact with the walls of the mold and adhering thereto and solidifying 65 thereon. Inasmuch as copper will not weld, these solidified splashing would be imperfectly absorbed by the casting, and thus constitute flaws called "cold-sets" which cause the splitting of the copper as the billet is subsequently being drawn into seam- 70 less tubing.

One of the objects therefore of the present invention is to eliminate this splashing and its harmful effects as described, by providing a mold which will permit the pouring of the metal to be commenced with an ascending stream entering the mold quietly and evenly from the bottom. This ascending stream fills the mold to such a depth 80 above the bottom that when the pouring from above is commenced, the descending stream plunges into the liquid copper in the bottom and does not splash. The pouring from above is of course not always necessary, the invention contemplating either a mold in which the pouring may be restricted to an ascending stream entering the mold from the bottom, or a mold utilizing both the ascending and descending streams as de- 85 scribed.

In the present embodiment of my invention the height of fall or drop of the descending stream (where used) is reduced to such a minimum that all splashing is eliminated, this entire elimination being impossible with molds under prevailing practice even where two superposed sections are used as previously described, the stream in its descent frequently coming in contact with 90 the walls of the molds, leaving a little copper adhering to said walls, which, as already stated, produces the objectionable "cold-sets" referred to.

The manner of overcoming the splashing with the descending stream under my invention, is by building up the mold by a series of sections whose height is reduced to a minimum, thus minimizing the height through which the stream need be poured. This height, in practice need not exceed nineteen inches, but obviously may be varied 100.

according to circumstances; and I do not wish to restrict myself to any precise pouring height.

The advantages of the invention will be best apparent from a detailed description thereof which is as follows:

Referring to the drawings, 1 represents the base of the mold, the same being composed of two sections or halves separable or 10 split along a vertical plane as clearly obvious from the drawings. The base 1 comprises a vertical leg *a* and a platform *b*, traversed by a conduit or "riser" *c* whose opposite ends are open to the influx and 15 discharge of the molten metal.

Surrounding the discharge end of the conduit *c* and formed on the platform *b* is an annular shoulder, boss, or ledge *d*, which enters the (cylindrical) passage-way 20 of the bottom tubular section 2 of the series of sections forming the mold proper; said shoulder *d* serving to center the said section 2 about the discharge end of the conduit *c* while said section is resting on the 25 platform *b*.

The upper end of the section 2 terminates in an outer annular shoulder *s* and an inner annular rim *r*, the latter being received by a corresponding annular recess *t* of the next 30 section 3 adapted to be superposed over the section 2, the rim *r* serving to center the section 3 about the axis of the section 2. The upper end of the section 3 in turn engages the top section 4, the connections between 35 the several sections being uniform throughout, that is to say the several sections are shouldered to one another, the topmost section being however left plain at the top as the rim *r* is not required. While I have 40 here shown three sections 2, 3, 4, in addition to the base 1, this number may be varied at will, and even reduced down to a single section (2) depending on the height of billet to be cast. The several sections are pref- 45 erably provided with annular peripheral ribs *h* for purposes of better handling and strengthening the same. In connection with the present invention I employ two ladles *L*, carried by suitable hoisting tackle *T*, suspended from a trolley carriage *E* traversing a rail *R*, well understood in the art, and 50 here shown in dotted outline merely.

The operation may be described as follows: The two sections or halves of the base 55 1 are first assembled and the bottom section 2 of the series of mold sections is deposited on the platform *b* as shown in Figs. 1 and 2, the middle and top sections 3, 4, (where no more are used), being conveniently placed 60 near by in preparation for easy and rapid transferring to their respective casting positions when desired. The molten copper is then brought from the furnace to the mold in two (or more) "bull-ladles" *L* suspended 65 from the overhead trolley as described, and

the operator of one ladle immediately commences pouring from his ladle into the runner or riser *c*, causing an ascending stream of copper to rise in the mold section 2. When this ascending stream of copper has 70 covered the bottom of the mold to such a depth (say that indicated by the line *w* in Fig. 2) that no splashing will occur when the pouring from above is started, the operator of the other ladle begins to pour into 75 the mold from above (see Fig. 2). This step is preferably begun before the ascending stream stops, and is continued until the level of the copper is close to the top edge 80 of section 2, when another operator quickly 85 places the section 3 in position. In the meantime the ladle is quickly raised to such an elevation that it is in position to pour into the newly placed section 3 as soon as it is placed; or the mold, which may be 90 supported on a movable carriage (not shown) is lowered to a proper pouring position. Pouring is immediately resumed, the interval during which the pouring is discontinued (to allow for the placing of the 95 section 3) being so short that the copper already in the mold has no chance to set or freeze over. When the section 3 is filled almost to the top, the section 4 is put in position, and so on until the required length or 100 height of casting has been obtained. When the casting has solidified or cooled somewhat, it is removed from the mold by sliding off the several cylindrical sections 2, 3, 4, 105 and so forth, and by separating the base 1 110 into its two halves. The copper which has been solidified in the "riser" is trimmed off and is returned to the furnace for remelting. It will be observed that the upper end of the section 2 is substantially on a level 115 with the top of the riser *c* when said section is deposited on the platform *b*; and when the section 3 is substantially deposited on the section 2 and the pouring of the copper 120 continued, the level of the copper in the section 3 will rise above the intake end of the riser *c*, and the molten metal seeking its own level would thus tend to run or back out 125 through the riser. This however does not happen in practice as the copper freezes in 130 the riser almost immediately after pouring ceases at that point, this being due to the fact that the cross-section of the riser is so small that the heat of the metal is very soon extracted by the surrounding mold. The frozen metal in the riser thus serves as a plug for the fluid metal poured successively into the sections 2, 3, 4, and so forth composing the mold. The sections 2, 3, 4, and so on while herein shown uniform in length need 135 not be so far as the present invention is concerned, although a uniformity in the length is perhaps ordinarily the most desirable.

I do not of course wish to limit myself to the precise details of the mold construc- 140

tion, or any part thereof, the same being susceptible of changes without departing from the nature or spirit of the invention.

Obviously the invention gives rise to a new method of casting, to wit, the pouring of the metal or charge from the bottom and top of the mold in succession; and while in the present illustration the cavity of the mold is such as to produce a casting of unitary cross-section throughout, I do not wish to be restricted to any particular form of casting, and accordingly wish to include molds which will produce any configuration, or cross-section of casting desired.

Having described my invention, what I claim is:

1. In combination with a mold comprising a series of independent hollow sections of uniform bore adapted to be assembled and form a continuous mold-cavity, said cavity being chargeable from the bottom and from the top of any given section, a base provided with a passage-way or riser delivering a rising stream of the charge to be cast through the bottom of the first section of the series, the cross-section of the riser being proportioned to cause a freezing of the charge therein before the charge in the mold reaches the level of the intake end of the riser.

2. A mold comprising a series of superposed removable intercommunicating sections of uniform bore collectively forming a mold-cavity to produce a casting whose depth for the casting position of the mold is not less than the diameter of any cross-section through the casting, a base coupled to the bottom mold-section, and provided with a riser or runner traversable by the charge, said riser operating to direct the charge in an ascending stream into and through the bottom of the lowermost mold-section, the upper end of any top mold-section being open to receive a charge through the top upon a given level reached by the ascending stream.

3. A mold provided with a cavity chargeable from a point above the bottom thereof and forming a casting whose depth for a casting position of the mold is not less than the diameter of any cross-section through the casting, said casting being separable from the mold by a relative movement of the parts in the direction of the axis of the mold, a hollow member chargeable from the top and discharging upwardly into said cavity through the bottom thereof, the dimensions of said hollow member being proportioned relatively to those of the cavity aforesaid, to cause a freezing of the charge in the hollow member while the charge in the cavity is still in a liquid condition.

4. A mold provided with a cavity charge-

able from the top and forming a casting whose depth for a casting position of the mold is not less than the diameter of any cross-section through the casting, said casting being separable from the mold by a relative movement of the parts in the direction of the axis of the mold, a member provided with a passage-way chargeable from the top and discharging upwardly into the cavity through the bottom thereof, the cross-section of the passage-way being proportioned to the dimensions of the cavity to effect a freezing of the charge in the passage-way while that in the cavity is still in a liquid condition.

5. A mold comprising a series of hollow intercommunicating sections of uniform bore shouldered to one another and detachably assembled, means for charging the bottom section of the series through the bottom of said section, the several sections being removable from the casing by a sliding movement of the sections in the line of the axis of the casting.

6. A mold comprising a series of hollow intercommunicating sections of uniform bore shouldered to one another and detachably assembled, a base comprising a platform for supporting the bottom section of the series, and a leg or member extending vertically to substantially the height of the bottom section of the series, said leg and platform being provided with a passage-way or riser chargeable from the top and discharging upwardly through the bottom of the bottom section of the mold, the cross-section of the riser being proportioned to effect a freezing of the charge poured thereinto and entering the bottom section of the mold, when said charge reaches a certain level in said section and is still in a liquid condition therein.

7. A mold provided with a cavity chargeable from a point above the bottom thereof and forming a casting whose depth for a casting position of the mold is not less than the diameter of any cross-section through the casting, a hollow member chargeable from the top and discharging upwardly into said cavity through the bottom thereof, the dimensions of said hollow member being proportioned relatively to those of the cavity aforesaid, to cause a freezing of the charge in the hollow member while the charge in the cavity is still in a liquid condition.

In testimony whereof I affix my signature in presence of two witnesses.

DANIEL TRACY.

Witnesses:

JOHN H. KLEPPINGER,
ROY A. LA MOTT.

It is hereby certified that in Letters Patent No. 1,148,939, granted August 3, 1915, upon the application of Daniel Tracy, of Great Falls, Montana, for an improvement in "Molds," an error appears in the printed specification requiring correction as follows: Page 1, line 60, for the word "steam" read *stream*; and that the said Letters Patent should be read with this correction therein that the same may conform to the record of the case in the Patent Office.

Signed and sealed this 7th day of September, A. D., 1915.

[SEAL.]

J. T. NEWTON,
Acting Commissioner of Patents.
